H. S. REYNOLDS.
SPUT FOR METALLIC RECEPTACLES.
APPLICATION FILED APR. 15, 1919.

1,332,687.

Patented Mar. 2, 1920.

Inventor:
Henry S. Reynolds,

By his Attorney C. W. Wood

UNITED STATES PATENT OFFICE.

HENRY S. REYNOLDS, OF BROOKLYN, NEW YORK.

SPUT FOR METALLIC RECEPTACLES.

1,332,687.

Specification of Letters Patent.

Patented Mar. 2, 1920.

Application filed April 15, 1919. Serial No. 290,259.

To all whom it may concern:

Be it known that I, HENRY S. REYNOLDS, a citizen of the United States, residing at Brooklyn, in the county of Kings and State 5 of New York, have invented certain new and useful Improvements in Sputs for Metallic Receptacles, of which the following is a specification.

This invention relates to metallic receptacles, such as casks, barrels and the like, having openings in the top or sides thereof for the passage of fluids and more particularly to an improved sput therefor, and to the method of attaching the same whereby 10 the opening in the receptacle may not only be reinforced but made fluid tight, the object of the invention being to provide an improved sput and method of attaching the same quickly and in an inexpensive manner without the necessity of welding it as was necessary heretofore, the present improvement having improved means whereby the turning of the sput relatively to the metal of the receptacle is positively prevented, and also having means whereby a 15 tag may be readily attached thereto.

In the drawings accompanying and forming a part of this specification, Figure 1 illustrates a cross section of the present improved sput attached to a part of a metal barrel and the plug therefor; Fig. 2 illustrates the first operation of attaching the sput and shows a cross section of the die and the punch; Fig. 3 illustrates the second and 20 final operation of attaching the sput and also shows a cross section of the die and punch; Fig. 4 is a plan view of the top of the sput prior to its attachment; and Fig. 5 is a modification of the means for attaching a tag to the sput.

Similar characters of reference indicate corresponding parts in the several figures of the drawings.

The present improved sput is an improvement in part on that shown in my contemporaneously pending application, Serial No. 271,484 filed January 16, 1919, in which the various advantages for sputs of this kind are more fully set forth.

It is necessary in attaching the sputs to the receptacles that provision be made for preventing the turning of the sput relatively to the receptacle when the closure or plug of the sput is screwed in or screwed out.

In my prior application I provided a series

of serrations in the bottom of an annular recess so that when the metal of the receptacle was forced into the recess it would engage the serrations and the sput thus be prevented from turning. This is entirely 60 practicable with receptacles when made of certain metal, but when the receptacle is made of steel and the sput as a malleable iron casting, it is somewhat difficult to force the steel into the serrations and therefore the 65 present improvement has to do with an improved sput whereby the positive turning of the sput relatively to the receptacle is prevented.

Moreover, as the metal of the receptacle 70 lies in close contact with the sput there has been no practicable way so far as I know, of attaching a tag to the sput and the present improvement provides means of accomplishing this in an efficient and simple 75 manner.

This improved sput 2 is provided with a central bore 3 suitably threaded for the reception of a plug 4, and its gasket 4'. The sput may be of annular form or have hexagonal or other form of sides, and is formed with a laterally or horizontally extending flange 5 and an upright or vertical integral locking flange 6, between which an annular recess 7 is formed, the side walls of 80 the locking flange being provided with a series of sharp upright projections or teeth 8. The annular recess 7 terminates in a comparatively abrupt shoulder 9, around which the edge 10 of the barrel is bent and locked. In 85 attaching this improved sput, it is placed in a suitable die 11 with the edge 10 of the barrel opening in juxtaposition to the annular recess 7 of the sput, and then by means of a punch 12 which is provided with a 90 recess 13 having an inclined side wall 14 terminating in a shoulder 15, the vertical integral locking flange is first forced outward and downward substantially to the position shown in Fig. 2. This operation 100 not only forces the edge of the metal opening into the annular recess, but it forces it down around the teeth.

In other words, this operation tends to tear the metal at the edge of the opening so 105 that portions of such edge project at each side of a tooth and thus prevent the turning of the sput with relation to the receptacle. Then, by means of a second punch 16 having the shape shown in Fig. 3, this vertical lock- 110

ing flange and a small portion of the teeth, which is formed integral with the locking flange are forced farther downward over the edge of the barrel or receptacle opening thereby forcing such edge 10 into the annular recess 7 and bending it around the shoulder 9 of such recess. By means of the teeth carrying the metal at the edge of the opening, any tendency of the sput to turn 5 relative to the head or side of the receptacle or barrel when a wrench is used to remove or tighten the plug is positively prevented. The inclined side of the punch hereinbefore referred to it will be observed flares the integral locking flange outward at the same 10 time that the shoulder of the punch forces the metal of the receptacle into the annular recess 7 of the sput.

The vertical integral locking flange, when 20 forced down has its top or outer surface 17 substantially flush with the metal of the barrel, and as this flange is of curved or beaded form it provides a neat and pleasing finish around the barrel opening. Preferably the flange terminates at its base in a shoulder 18, which facilitates the formation 25 of the bendable locking flange.

Thus, I am enabled by a couple of punching operations, to, as it were, cold weld the 30 metal body edge into the annular recess of the sput and lock the same therein by means of a locking flange forced down upon the metal of the body in such manner that the free edge of the flange will be flush with or 35 slightly below the shoulder 19 of the barrel metal formed by its bend over the relatively abrupt shoulder 9 of the sput, so that the edge of the barrel opening will have substantially an ogee bend and any possibility 40 of the barrel pulling away from its locking recess and flange prevented, not only by the flange but by the shoulder 9. At the same time a fluid tight joint is positively obtained by this simple mode of procedure through 45 the medium of this improved sput.

For the purpose of attaching a tag, I provide in one form of the improvement a projection or ear 20 formed integral with the sput, and which projection is provided with 50 a groove 21 whereby the wire of the tag may be threaded therethrough or instead of forming the sput with a projection integral therewith, I can provide the sput with a pair of openings 22 connected on the under 55 side with a groove 23 whereby a wire may be threaded through the openings in a manner which will be readily understood for the attachment of a tag.

I claim as my invention:

60 1. A sput for a metallic receptacle having an annular flange, and a vertical integral bendable locking flange having therebetween an annular recess provided with a shoulder, said vertical bendable locking flange having at the side thereof a plural-

ity of upright teeth in position and effective to engage the free edge of the receptacle opening to which the sput is attached.

2. A sput for a metallic receptacle having an annular flange, and a vertical integral 70 bendable locking flange having therebetween an annular recess provided with a shoulder, said vertical bendable locking flange having at the side thereof a plurality of upright teeth in position and effective to 75 engage the free edge of the receptacle opening to which the sput is attached, and said sput having means for the attachment of a tag wire.

3. A metallic receptacle having an opening, a sput having a laterally extending flange, and an integral bendable locking flange having therebetween an annular recess with the edge of the opening clamped in said recess by said bendable locking 85 flange, said sput also having a plurality of upstanding teeth in position to tear the free edge of the opening and thereby prevent the turning of the sput relatively to the receptacle. 90

4. A metallic receptacle having an opening, a sput having a laterally extending flange, and an integral bendable locking flange having therebetween an annular recess with the edge of the opening clamped 95 in said recess by the locking flange, said recess also having a shoulder around which the edge of the receptacle is bent and said locking flange having at the side thereof a plurality of upright teeth for tearing the 100 free edge of the opening thereby to prevent the turning of the sput relatively to the receptacle.

5. A metallic receptacle having an opening, a sput having a threaded bore, a laterally extending flange, and an integral bendable locking flange having therebetween an annular recess having an abrupt shoulder and also having a plurality of upright teeth at the side of the integral flange, the metal 110 of the receptacle being clamped in said recess by bending the locking flange over the edge of such metal thereby to force the free edge of said receptacle opening into engagement with the teeth. 115

6. A metallic receptacle having an opening, a sput having a threaded bore, a laterally extending flange, and an integral bendable locking flange having therebetween an annular recess having an abrupt shoulder 120 and also having a plurality of upright teeth at the side of said locking flange, the metal of the receptacle being clamped in said recess by bending the locking flange over the edge of such metal, the surface of the locking flange being substantially flush with the surface of the adjacent metal and the free edge of the receptacle opening in position to be engaged by said teeth. 125

7. A receptacle having an annular open- 130

- ing, a sput having an annular recess for the reception of the edge of such opening, and an integral locking flange provided at the side thereof with a plurality of upright 5 sharp formed projections, said integral locking flange clamping the edge of said receptacle into the recess of said sput, said recess terminating in an abrupt shoulder around which the edge of the receptacle is 10 bent and said projections serving to tear the free edge of the metal opening of the receptacle thereby to prevent the turning of the sput relatively to the receptacle.
8. A sput for a metallic receptacle having 15 an annular flange provided with a grooved passage for the reception of a tag wire.
9. A sput for a metallic receptacle having an annular flange provided with means for the attachment of a tag wire and also 20 having a vertical integral locking flange, a plurality of upright sharp projections, and an annular recess.
10. A sput for a metallic receptacle having an annular flange provided with means 25 for the attachment of a tag wire and also having a vertical integral locking flange, a plurality of upright sharp projections, and an annular recess provided with a shoulder.
11. A metallic receptacle having an open- 30 ing, a sput having an integral bendable locking flange provided at one side thereof with a plurality of sharp upright projections, and an annular recess with the edge of the opening clamped in said recess by said locking 35 flange with the free edge of said opening in engagement with the sharp projections thereby to prevent the turning of the sput relatively to the receptacle.
12. A sput for a metallic receptacle having 40 an annular recess, and a vertical integral bendable locking flange provided at the side thereof adjacent to its base with upright teeth.
13. A sput for a metallic receptacle having 45 an integral vertical bendable locking flange having at the side thereof adjacent to its base upright teeth.
14. A sput for a metallic receptacle having 50 an annular recess, and a vertical bendable integral locking flange provided at the side thereof adjacent to its base with upright teeth, said sput also having an annular flange at the outer side of said annular recess.
15. The method of attaching a sput to the circular opening of a metal receptacle, which 55 consists in providing a sput with an annular recess, a shoulder, an integral bendable locking flange having upright teeth, and then forcing the locking flange outwardly and downwardly into engagement with the edge 60 of the metal thereby to clamp the same around such shoulder and into the sput recess and at the same time tear the free edge of the metal opening by means of such teeth thereby to prevent the turning of the sput 65 relatively to the receptacle.
16. The method of attaching a sput to the circular opening of a metal receptacle, which consists in providing a sput with an annular recess having an abrupt shoulder, 70 and an integral bendable locking flange having at the side thereof upright teeth, and then forcing the locking flange outwardly and downwardly step by step into engagement with the edge of the metal thereby to 75 clamp the same around the shoulder and into the sput recess and at the same time tear the free edge of the metal opening by means of the teeth thereby to prevent the turning of the sput relatively to the metal.
17. The method of attaching a sput to the circular opening of a metal receptacle, which 80 consists in attaching a sput with an annular recess having an abrupt shoulder, and an integral bendable locking flange provided with upright vertical teeth, and then forcing the locking flange outwardly and downwardly by a plurality of punching operations into engagement with the edge of the metal thereby to clamp the same around said shoulder and into the sput recess and at the same 85 time tear the free edge of the metal opening by means of the teeth thereby to prevent the turning of the sput relatively to the receptacle.
- Signed at New York city in the county of New York and State of New York, this 11th day of April 1919.
- HENRY S. REYNOLDS.
